(57) **CLAIM**

The ornamental design for a hitch step with light, as shown and described.

DESCRIPTION

FIG. 1 is a perspective view of a hitch step with light, showing our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines in the drawings that are immediately adjacent to the shaded areas define the boundaries of the claimed design. All other broken lines in the drawing illustrate portions of the hitch step with light. The broken lines form no part of the claimed design.
